168,482

AIRPLANE

Chester V. Sol and Paul Graban, Hobart, Ind.

Application June 25, 1952, Serial No. 20,344

Term of patent 3½ years

(Cl. D71—1)

To all whom it may concern:

Be it known that we, Chester V. Sol and Paul Graban, citizens of the United States, residing at Hobart, in the county of Lake and State of Indiana, have invented a new, original, and ornamental Design for an Airplane, of which the following is a specification, reference being had to the accompanying drawing, forming part thereof.

Figure 1 is a side elevational view of an airplane, showing our new design;

Figure 2 is a top plan view thereof;

Figure 3 is a rear elevational view; and

Figure 4 is a front elevational view of the same.

We claim:

The ornamental design for an airplane, as shown.

CHESTER V. SOL.
PAUL GRABAN.
